LAMP MOUNT AND COMPONENT THEREFOR
Frederick W. Hoeh, Livingston, N.J., assignor to Westinghouse Electric Corporation, Pittsburgh, Pa., a corporation of Pennsylvania

Filed Aug. 20, 1963, Ser. No. 303,247
9 Claims. (Cl. 313—204)

This invention relates to electrical devices and has particular reference to an improved mount and component for electric lamps and an arrangement for attaching a wire support member or the like to a lamp stem.

In the manufacture of fluorescent and incandescent lamps it is frequently desirable or necessary to attach a component, such as a wire support or the like, to the lamp stem without connecting it electrically with the lead-in wires. For example, in certain types of fluorescent lamps using a mixture of neon and argon as a fill gas it has been found that the efficiency can be increased by placing an electrically floating grid a predetermined distance in front of each cathode. Such floating grids and the manner in which they operate and reduce the anode voltage drop is disclosed in U.S. Patent No. 2,725,497 to J. J. Mason. In the case of incandescent lamps, an insulated auxiliary support member is frequently required to prevent the central portion of the suspended filament from sagging during use.

In the prior art, such grids and auxiliary supports were attached to the glass stem by embedding the end of the support wire into the stem press after the latter has been heat softened. Since such stems are made on automated high speed machines, the insertion of such members into the press introduces quality control problems and in many cases is impractical where the size or shape of the member prevents it from being automatically oriented and fed into the machine heads. As a result, it was necessary in such instances to reheat the press portions of completed stems and insert the ends of such specially shaped components into the press by hand. This was not only tedious but inefficient and costly.

With the foregoing in mind, it is the general object of the present invention to provide an improved mount construction for electrical devices such as lamps or the like which includes a component, such as a grid or support wire, that can be very conveniently and inexpensively attached to otherwise completed stems solely by a mechanical interfitting of the parts.

Other objectives, in addition to those which will occur to those skilled in the art, are the provision of a pre-formed wire member that can be securely locked in place on a stem in the aforesaid manner without reworking the glass stems thereof.

The foregoing objects, and other attendant advantages, are achieved in accordance with the present invention by bending the end of the wire member that would be normally embedded in the stem press into an enlarged compressible clip or the like of such size that, when in compressed condition, it can be inserted into the exhaust aperture and adjoining portion of the exhaust tube normally employed in lamp stems. The resultant tensioning of the clip by the tube mechanically locks the member in place on the stem. Thus, the grid or support member is held in the desired position on the stem solely by mechanical means and the final assembly of the mount can be accomplished quickly and efficiently without any reworking of the glass.

A better understanding of the invention will be obtained from the accompanying drawing, wherein:

FIGURE 1 is an elevational view of a fluorescent lamp having mounts with floating grid members which embody the invention, portions of the envelope at each end being broken away to show the mount structures;

2

FIG. 2 is an enlarged perspective view of one of the lamp mounts before it is sealed into the envelope; FIG. 3 is a side view of the mount;

FIG. 4 is a sectional view through the mount along the line IV—IV of FIG. 2, showing the manner in which the stem and wire grid member inter-lock one with another;

FIG. 5 is an enlarged perspective view of the combined grid-and-support member shown in the preceding figures; and

FIG. 6 is an alternative embodiment illustrating the application of the invention to an incandescent lamp mount.

While the present invention can be used with advantage in various types of electrical devices having apertured stem or mount assemblies, it is particularly adapted for use in conjunction with fluorescent and incandescent lamps and has, accordingly, been so illustrated and will be so described.

20

Embodiment I

In FIG. 1 there is shown a fluorescent lamp 10 which includes the usual tubular envelope 12 having electrode mounts 14 sealed into each of its ends, which mounts are provided with the improved floating grid members 34 of the present invention. The inner surface of the envelope is coated with a layer 18 of suitable phosphor in the conventional manner and a charge of mercury and inert fill gas such as neon, argon, or mixtures thereof are sealed within the envelope in accordance with standard lamp-making practice.

As shown more particularly in FIG. 2, the lamp mount 14 consists of a vitreous or glass stem 20 that has a flared skirt 22 at one end and a press 24 at its opposite end. A glass exhaust tube 26 extends axially within the stem 20 and is sealed to an interior part at a point immediately below the press 24 so as to merge and communicate with an exhaust aperture 28 provided in the side of the stem wall. While only one of the mounts of a fluorescent lamp normally has such an exhaust aperture and tubulation, the lamp 10 of the present invention departs from the prior art practice in that both mounts are of the same construction, one of the tubes being used as a dummy and remaining open if desired.

Returning to FIG. 2, the usual pair of lead-in wire conductors 30 are sealed through the stem press 24 and have an elongated cathode 32 attached to their upwardly extending ends. The cathode consists of either a coiled-coil or triple-coiled filament of tungsten wire that is coated with suitable emission material, and it is preferably supported in a plane substantially normal to the stem axis as here illustrated.

As shown in FIG. 2, and more particularly in FIGS. 3 to 5, the combined grid-and-support member 34 of the present invention consists of a preformed member fabricated from a single piece of resilient but relatively stiff wire one end of which is formed into a flat spiral 36 of approximately three turns with a $1/4$ " pitch and the other end of which is bent into an enlarged spring clip 42 of generally U-shaped configuration that is compressible. The clip portion 42 is located within the end of the tube 26 that adjoins the aperture 28 and is of such dimension that, when compressed, it can be inserted through the aperture and snugly fits within the tube. By virtue of the natural resiliency of the wire, the clip portion 42 expands after it has been inserted into the stem 20 and presses against the sides of the tube 26 thereby locking the wire member 34 in the desired position on the stem.

The spiral grid portion 36 is preferably disposed in a plane substantially normal to the stem axis and is supported in this position by a substantially straight arbor

portion 38 located between the grid portion and an arcuate intermediate portion 40. The arbor portion is of such length that the spiral grid structure 36 is disposed a predetermined distance, about $\frac{1}{4}$ " for example, in front of the electrode 32 and in a plane that is substantially parallel to the electrode plane.

Preferably, the intermediate curved portion 40 has a shape that conforms to the profile of the press 24 so that it fits snugly around this portion of the stem 20, as shown in FIGS. 2 to 4. In addition, the segment of the intermediate portion 40 adjoining the clip portion 42 is provided with a reverse bend so as to provide a nodule or projection 41 that engages and is seated behind the peripheral lip or rim portion of the stem wall that defines the aperture 28. Thus, the intermediate portion 40 desirably comprises a generally C-shaped loop or eyelet, as shown most clearly in FIG. 5. In addition to automatically controlling the depth of insertion of the wire member 34 into the tube 26, the interaction between the curved intermediate portion 40 and the rim and press portions of the stem 20 prevents the wire member from becoming displaced either in a lateral or axial direction from its assembled position. The grid structure is thus securely locked on the stem 20 in predetermined spatial relationship with the cathode 32 solely by the force interfitting of the members and the resulting spring-lock action.

As a specific example, satisfactory results in the case of a 40 watt "preheat" type fluorescent lamp have been obtained by fabricating the grid-and-support member 34 from No. 446 stainless steel wire approximately 20 mils in diameter and by making the arbor portion 38 of such length that the spiral grid structure 36 was located approximately $\frac{1}{4}$ inch in front of the cathode. Comparative tests have shown that this type of grid structure, when used in combination with a 40% neon-60% argon fill gas mixture, increased the lumen output by approximately 7% and reduced the lamp watts from 42 to about 40.5 watts. Thus, the light output was increased without the concomitant increase in watts which tends to overload the operating circuit and normally results when a neon-argon fill gas mixture is used.

Since the grid structure is electrically isolated from the cathode, substantially all of the discharge current on the anode half cycle passes through the cathode in contrast to the situation which obtains when plate type anodes are used and are connected to the lead wires in parallel with the cathode. This increases the cathode temperature and affords the additional advantages of increasing the life of such "preheat" lamps and reducing discoloration.

Assembly of the grid-support member 34 with the stem 20 is very conveniently accomplished by first compressing the clip portion 42 and inserting it into the aperture 28 of the otherwise completed mount 14, and then forcing the clip into the tube 26 until the curved intermediate portion 40 seats against the rim of the aperture. This curved portion is then pressed downwardly over and against the press 24 and inwardly into the aperture until the nodule 41 slips over and is caught behind the overhanging portion of the rim that is located directly below and adjacent to the press.

Embodiment II

As shown in FIG. 6, the invention is not limited to electric discharge devices or fluorescent lamps but may also be used with advantage in incandescent lamps. In this case, the mount 14a includes the usual glass stem 20a having a press 24a, exhaust tubulation 26a and side aperture 28a as in the case with the fluorescent mount described previously. As will be obvious however, the upper ends of the lead-in wires 30a are much longer, as is the coiled filament 44.

In the illustrated embodiment, the wire member 34a is used as an auxiliary support and its upper portion or

arbor 38a is substantially straight and terminated by a small eyelet or loop 46 that encircles an intermediate portion of the filament. The clip portion 42a and the curved intermediate portion 40a are constructed and interlock with the stem in the same manner as in the above-described fluorescent lamp mount. It will be observed, however, that in both mounts the upper ends of the one-piece wire members are terminated by an arcuate loop or spiral of at least one turn.

It will be appreciated from the foregoing that the objects of the invention have been achieved in that a novel structure has been provided for attaching a support or grid element to a lamp mount solely by mechanical means. This permits grid structures or auxiliary supports to be preformed and subsequently quickly assembled on a mass production basis with otherwise completed lamp mounts without the critical glass-working and inserting operations heretofore required.

While several embodiment have been illustrated and described, it will be understood that various modifications can be made without departing from the spirit and scope of the invention. For example, the compressible clip portion can be made as a separate element and fastened, as by welding, to another member to form a two-piece instead of a one-piece component.

I claim as my invention:

1. A mount for an electric energy translation device comprising,
a vitreous stem having a press at one end,
an electric energy translation element supported in predetermined spatial relationship with said stem by means anchored in said press,
a tubulation extending within and joined to said stem and communicating with an aperture therein located proximate said press, and
an elongated member extending through said aperture and disposed in predetermined spatial relationship with said electric energy translation element,
said member being held in such position solely by means of an attached compressible element that is located in and interlocked with the end of said tubulation that adjoins said aperture.
2. A mount as set forth in claim 1 wherein: said tubulation comprises a vitreous tube that is fused to said stem, and said compressible element comprises an integral part of said elongated member.
3. A mount for an electric discharge device comprising,
a vitreous reentrant stem having a press at one end,
an electrode supported in predetermined spatial relationship with said stem by means embedded in said press,
a vitreous tube extending within and fused to said stem and communicating with an aperture therein located near said press,
a grid located a predetermined distance in front of said electrode, and
means holding said grid in such position comprising a support wire having one end joined to said grid and its opposite end formed into a compressible clip that is forcibly inserted into said tube through said aperture and is locked therein solely by the tensioning of said clip by said tube.
4. A mount as set forth in claim 3 wherein said grid is integral with the support wire and constitutes the free end thereof.
5. A mount for a fluorescent lamp comprising,
a vitreous reentrant stem having a flared skirt at one end and a press at its other end,
lead-in conductors embedded in and extending beyond said press,
a filamentary electrode connected to and supported by the protruding portions of said lead-in conductors,
a vitreous tube extending axially into said stem and sealed to an interior part thereof,

said stem having an aperture therein that is located below said press and merges with the bore of said tube to define a continuous passageway, and a combined grid-and-support member comprising a length of wire having a compressible clip formed at one end and its opposite end formed into a grid structure, 5 the compressible clip portion of said length of wire being located in and compressively locked within the tube and the intermediate portion thereof extending through the aperture and axially beyond the press so that said grid structure is supported in a predetermined position in front of said electrode solely by the force-interfitting and resulting spring interlocking of said clip portion and tube.

6. A fluorescent lamp mount as set forth in claim 5 wherein: the grid portion of said wire comprises a flat spiral of approximately three turns that is disposed in a plane transverse to the stem axis, and a segment of the wire adjacent said clip portion is provided with a reverse bend that is caught behind the aperture-defining lip portion of said stem located below the press and thereby prevents axial displacement of the wire grid-and-support member from its assembled position on said stem.

7. A fluorescent mount as set forth in claim 5 wherein: said electrode is of elongated configuration and is disposed in a plane that is transverse to the stem axis, said grid structure is disposed in a second plane that is substantially parallel to and spaced approximately $\frac{1}{4}$ " in front of the electrode plane, and said grid-and-support members is fabricated from stainless steel wire.

8. A mount for an electric lamp or the like comprising,

a vitreous stem having a press and an opening therein located adjacent said press, a tube sealed to the underside of said stem at a point such that it communicates with the opening therein, lead-in wires sealed through and extending beyond said press,

an elongated incandescent element having its ends attached to and supported by said lead-in wires, and an auxiliary filament-support means comprising a wire member one end whereof is coupled to an intermediate portion of said incandescent element and the other end whereof is formed into a spring clip that is disposed in and compressively locked within the portion of said tube that adjoins said opening.

9. A self-supporting element adapted for use in an electrical device having a stem with a press at one end and a tubulation that is joined to its opposite end and communicates with an aperture in the stem wall, which element comprises a preformed length of wire having, 15 a compressible clip at one end larger in dimension than the bore of said tubulation, an intermediate portion having a reverse bend that defines a nodule adapted to engage the aperture-defining rim portion of said stem, 20 an arbor portion of predetermined length extending from said intermediate portion, and an arcuate portion that constitutes the opposite end of said wire and defines a substantially closed loop.
